UNITED STATES PATENT OFFICE.

HERMAN C. FUHRMAN, OF MARION, IOWA.

VALVE-SEATING TOOL.

Application filed September 27, 1926. Serial No. 137,910.

This invention relates to the dressing of gasoline engine valve seats, and the object of the invention is to provide a tool whereby a faulty valve seat may be prepared for grinding, or the cutting action of a fine reamer.

In most cases the valve-seats of explosion engines needing re-grinding are found to be covered with a scale of baked and beaten carbon almost as hard as glass. If the surface 10 happens to be comparatively uniform the valve and seat may be ground together by means of a sharp abrasive, without excessive wearing away of the valve or seat. But in many cases the seat will have high spots 15 coated with this hard glaze, and these need to be leveled down preliminary to the grinding operation. This is usually done with a fluted reamer having cutting edges disposed at the proper angle for the seat. The work, 20 however, is very injurious to the reamer, as it dulls the edges rapidly, when the reamer must be reground. This is a nice and slow operation, and can only be done in a special grinder fitted for the purpose.

25 This invention aims to dispense with the reamer in some cases, and in all cases where its use is necessary, to save the cutting edges and prolong the usefulness of the reamer by removing the glassy scale and leaving for the 30 work of the reamer only clean iron.

In the accompanying drawing, forming a part of this specification, Fig. 1 is a side elevation of a tool embodying my invention as in use, the valve seat being shown in section. 35 Fig. 2 is a plan view of the tool as seen from below. Fig. 3 is a section of the same to the right of the line 3—3 of Fig. 1.

In the drawing, the numeral 5 denotes a fragment of an engine block containing the 40 valve-seat 6. A guide 7 for the stem of a valve is herein shown as a bushing. These vary in diameter, and any reaming tool intended for general work will need a set of spindles 8 with shafts varying in diameter 45 to fit the various valve guides. It is contemplated that the spindle for this tool would also serve for a reamer as well.

The spindle carries a conical head 9, suitably attached, as by a nut 10. The conical face of the head corresponds to the angle of the valve and seat. Parallel with this face are bored a number of seats 11 for scrapers 12. The seats, which are preferably cylindrical, open with a narrow slot outwardly, 55 so that the scrapers set therein project a lit-

tle beyond the conical surface, and are thus adapted to bear on the valve-seat as the tool is turned. The scrapers, as herein shown, are cylindrical sections of roughened and hardened steel, correspondingly practically 60 to sections of rat-tail files. They are secured in place by set-screws 13 having tapered heads, as shown in Fig. 3.

It will be evident that a few turns of the tool when in the position shown in Fig. 1, 65 will by abrasion quickly remove the glassy carbonized surfaces of the valve seats, but the face of the head will prevent the scrapers from digging into the seat between such hard spots and making a wavy, uneven surface. 70 Once the hard scale is removed the seat may be finished, by grinding the valve and seat directly, or by truing with a cutting reamer before the grinding operation.

The roughened bits or scrapers being made 75 fast in their seats, their action is a positive abrasion by scraping. The bits may be tempered very hard, so as to peel off the hardest scale that may form on the valve-seat. When they dull, as of course they will in time, fresh 80 abrading surfaces may be brought to bear on the work by turning the bits, sliding them endwise, or reversing them. When finally worn out they are replaced by new ones, at 85 a trifling cost.

I claim:

1. A valve-seat tool, comprising a spindle with a shaft fitting revolvably in the valve-stem guide, a head attached to the spindle, and having cylindrical radial bit-seats with 90 solid backs formed in the body of the head, the seats opening outwardly their full length in narrow gaps to permit a slight projection of the bits, and straight, cylindrical and reversible roughened bits mounted immovably 95 in said seats.

2. In a valve-seat tool, a spindle fitted to revolve in the valve-stem guide, a frusto-conical head secured to the spindle, and having cylindrical radial seats for abrading bits 100 formed in the solid body of the head, and opening outwardly their full length in narrow gaps to permit a slight projection of the peripheries of the bits, a series of cylindrical, reversible, rough-faced bits set in said seats, 105 and conical set-screws disposed in the head and adapted to press the bits outwardly into said gaps.

In testimony whereof I affix my signature.
HERMAN C. FUHRMAN.
